By his attorney R. S. A. Lacey

UNITED STATES PATENT OFFICE.

MARION JASPER BARROW, OF NEW BLOOMFIELD, MISSOURI.

MOTOR.

SPECIFICATION forming part of Letters Patent No. 375,410, dated December 27, 1887.

Application filed July 13, 1887. Serial No. 241,178. (No model.)

To all whom it may concern:

Be it known that I, MARION JASPER BARROW, a citizen of the United States, residing at New Bloomfield, in the county of Callaway and State of Missouri, have invented certain new and useful Improvements in Motors; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 This invention relates to motors for drills, mixers, churns, and for general use.

The improvement consists in the novel features presently to be described and claimed, and shown in the annexed drawings, in which—

Figure 1 is a perspective view of a motor embodying my invention; Fig. 2, a side view, parts broken away, of the device, showing the operation of the folding-stand by dotted lines; 25 Fig. 3, a section on the line X X of Fig. 1; and Fig. 4 a detail view, parts being broken away, of the roller-guides for the strap or cord and the spindle.

The object of this invention is the production of a simple, cheap, and efficient motor, which can be readily adapted to different classes of work, and which is easily managed and not liable to get out of repair.

The frame of the device is composed of the 35 standards A, the sill B, and the top and cross-frames C, which form supports for the guide-rollers D and the guide-rollers E at each end of the rollers D. The rollers E form guides for the spindle F, and are held in place against 40 the same by the strap or cord G, which passes over said spindle and between the guide-rollers D and receives a continuous or back-and-forth motion from any suitable source of power, manual power being preferred, for

45 which purpose the ends of the strap are provided with the handles g. The spindle is reduced opposite the guide-rollers E, forming grooves f, in which said rollers E are fitted for preventing the longitudinal movement of the 50 spindle relative to said guide-rollers D and E. The guide-rollers D and the guide-rollers E at each end thereof may have separate journals;

but for compactness and economy of construction they are mounted on a single journal or shaft, H. It is essential that the rollers D and 55 E be separated, as they revolve at unequal speeds, otherwise lost motion would result. The spindle is preferably tubular, and is adapted to receive the stem or shaft I, which may be a drill or a dasher shaft, the latter being shown, which is secured therein at any adjusted position by the set-screw i. The sill is provided with the adjustable rest J, which is curved on its forward edge and held to the sill in an adjusted position by the set-screw j' 65 extending through the slot j, formed in the rest.

The folding stand is composed of the side bars, K, which embrace the standards, and are secured thereto at their inner ends by the set-screws or bolts k' passing through the slots k, 70 and the cross-bars L, which unite the outer ends of the side bars. The sill B projects at each end a short distance beyond the standards, forming stops b, which support the side bars on each side of the set-screws k' and hold 75 the stand unfolded.

To fold the stand it is pulled forward until the ends of the side bars clear the rear stops, b, when it is tilted and closed, as shown by dotted lines in Fig. 2.

Having thus described my invention, what I claim, and desire to secure by Letters Patent, is—

1. The combination, with the standards, the cross-beams, and the guide-rollers D, of the 85 spindle, and the strap passed over the spindle and between the guide-rollers D, substantially as and for the purpose specified.

2. The combination, with the guide-rollers D and the guide-rollers E, at each end thereof, 90 and suitable supports for said guide-rollers, of the spindle resting against and reduced opposite the guide-rollers E, and the strap passed around the spindle and between the guide-rollers D, substantially as and for the 95 purpose specified.

3. The combination of the cross-beams, the vertical shafts H, the guide-rollers D, and the guide rollers E, at each end thereof, mounted on said shafts, the spindle resting against and 100 reduced opposite the guide-rollers E, and the strap passed around the spindle and between the guide-rollers D, substantially as described.

4. The combination, with the guide-rollers

D and the tubular spindle provided with means, as the set-screw, for holding a shaft therein, of the strap passed around the spindle and between the guide-rollers D, substantially as set forth.

5. The combination of the frame composed of the sill, the standards, and the cross-beams, the guide-rollers D, journaled vertically between the cross-beams, the spindle, strap, and the adjustable rest, located between the standards and secured to the sill, substantially as set forth.

6. The combination, with the standards and

the sill projected at each end forming stops, of the folding stand secured to the standards 15 between and held distended by said stops, and adapted to have a longitudinal movement for disengaging it from the stops, substantially as and for the purpose specified.

In testimony whereof I affix my signature in 20 presence of two witnesses.

MARION JASPER BARROW.
